UNITED STATES PATENT OFFICE

FRANCIS M. MULLIGAN, OF BUTTE, MONTANA

FIGURE WHEELED TOY

Application filed May 8, 1929. Serial No. 361,399.

This invention relates to improvements in figure wheel walking toys, and more particularly to toys adapted to simulate the natural movements of animals when the toy is drawn across the ground or other surface.

One of the objects of the invention is to provide a toy consisting of a cart or other vehicle drawn by either a two, or four legged animal, in which the animal is adapted to go through its natural movements while walking, without swaying or rocking the vehicle.

Another object is to produce a device of the character described in which the maximum simplicity of construction and operation is secured.

Other objects and advantages will appear as the nature of the improvements is better understood, the invention consisting substantially in the novel arrangement and correlation of parts herein fully described, and illustrated in the accompanying drawings, wherein similar reference characters are used to describe corresponding parts throughout the several views, and then finally pointed out and specifically defined and indicated in the appended claims.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive standpoint.

In the drawings forming a part of this specification

Figure 1 is a side view in elevation of one embodiment of the invention.

Figure 2 is a top plan view thereof partly in section.

Figure 3 is a rear view of my improved toy and

Figure 4 is a side view in elevation of a modified form of my invention.

Referring now to the drawings in detail 5 indicates the base of a cart 5^a, the said base being provided with depending lugs 6 and 7 in which lugs there is rotatably mounted a shaft or axle 8 having ground engag-

ing wheels 9 and 10 secured thereto. The base 5 is provided with a cutout or recess 11 into which extends a shaft 12 projecting or extending from the body portion 13 of a figure of an animal, in the present instance 55 that of a duck. The said shaft 12 is movably supported in the recess 11 by means of a strap 14 secured to the front of the base 5, and by means of a screw 15 threaded into the rear end of the said shaft and rotatably mounted in a bracket 16 secured to the base 5.

The duck body 13 of the toy is provided with an opening 20 in which there is glued or otherwise secured a cylindrical post 21 which extends beyond the said body on both sides thereof. A pair of wings 22 and 23 are movably supported on the said extending portions of the post 21 and are slightly spaced from the body 13 by means of washers 24. Legs 25 and 26 are movably supported on screws 27 and 28 which are threaded into the ends of the post 21. A pin 29 is swingingly supported in a staple or other support 30 secured to the post 21. The 70 said pin 29 extends through a series of slots 31 in the body 13, wings 22-23, and the washers 24 and engage openings 32 and 33 in the legs 25 and 26 so as to connect the said legs. The leg 25 is provided with a 80 foot portion 35 and the leg 26 with a similar foot portion 36 and each of these foot portions has a ridge or raised portion 37 extending the entire length of the said feet. The bottom or ground engaging surfaces of 85 both the ridges and foot portions are arcuate or cylindrical and the said arcs are struck from the center of the pivot screws 27 and 28. It will be noted that the ridges 37 are located on the extreme inside of the feet so as to support the weight of the figure portion of the toy near its center of gravity 90 thus permitting the toy to readily sway from side to side when the toy is operated, as will hereinafter be described.

To operate the toy, it is drawn across the ground or floor by means of a draw cord or string 40 secured to the beak of the duck. As the wheels 9 and 10 rotate they carry with them the shaft 8 to which is secured a cam 106

41 provided with a cam groove 42, which groove will actuate a pin 43 depending from the shaft 12 and rock the said shaft causing the body of the duck to sway or wabble from side to side. As the toy is drawn along either one or the other of the feet of the duck will be in contact with the ground which will cause the said foot to roll on its ground engaging surface and swing the pin 29 to actuate the adjacent leg to move forwardly and simultaneously rock or sway the body to the side of the ground contacting foot owing to the rocking of the shaft 12 and the raised ridge 37. The pin 29 will also simultaneously with the movement of the foot cause the wings 22 and 23 to swing up and down on the post 21.

jection on the shaft extending into the cam groove to sway the figure from side to side when the wheels are drawn along the ground, and means connecting the legs to cause the rearward movement of one of them to move the other in a forward direction. 70

FRANCIS M. MULLIGAN.

In Fig. 4 I have shown a modified form of my invention in which I have substituted a four legged animal for the two legged one shown in Figures 1 to 3. In this form the rock shaft 12 is secured to a bifurcated yoke 50 which in turn is secured to the body 51 of a horse by means of a cross bar 52 secured to both the yoke and horse body. Each pair of legs 53 and 54 may be actuated for movement by a pin and slot arrangement similar to the one employed in the duck or in any other suitable manner.

30 From the foregoing it will be seen that I have provided a toy adapted to employ either a two legged or four legged animal in combination with a vehicle and means between the said vehicle and animal which will cause 35 same to simulate the natural body movement while walking without affecting the movement of the vehicle.

Having described my invention what I claim as new and desire to secure by Letters Patent is

10. A toy of the nature described, comprising a vehicle, a recessed base on the vehicle, a pair of depending lugs on the base, an axle rotatably mounted in the said lugs, a pair of ground engaging wheels on the axle, a grooved cam secured to the axle, a toy figure, a shaft on the figure extending into the recess, a bracket on the base extending into the recess, a screw extending through the bracket into the end of the shaft to rockingly support same, and a projection on the shaft extending into the cam groove for the purpose specified.

2. A toy of the nature described, comprising a vehicle, a recessed base on the vehicle, a pair of depending lugs on the base, an axle rotatably mounted in the said lugs, a pair of ground engaging wheels on the axle, a grooved cam secured to the axle, a toy figure, a leg pivotally mounted on each side of the figure, a shaft on the figure extending into the recess, a bracket on the base extending into the recess, a screw loosely mounted in the bracket and extending into the rear end of the shaft to rockingly support same, a pro-
